UNITED STATES PATENT OFFICE

145,649

DESIGN FOR A PIANO

Alfons Bach, New York, N. Y.

Application May 23, 1945, Serial No. 119,682

Term of patent 14 years

(Cl. D56—9)

To all whom it may concern:

Be it known that I, Alfons Bach, a citizen of the United States, residing at New York, in the county of New York, State of New York, have invented a new, original, and ornamental Design for a Piano, of which the following is a specification, reference being had to the accompanying drawing, forming part thereof.

Fig. 1 is a front perspective view of the piano, showing my new design.

Fig. 2 is an enlarged fragmentary front elevational view of the end construction, illustrating the contour of the keyboard unit.

The back of the piano is plain, and the end not shown is of the same appearance as the end illustrated.

I claim:

The ornamental design for a piano as shown and described.

ALFONS BACH.
